UNITED STATES PATENT OFFICE.

JOHN AUERMILLER, OF CHICAGO, ILLINOIS.

WINDOW AWNING.

1,418,860.

Specification of Letters Patent. Patented June 6, 1922.

Application filed November 29, 1920. Serial No. 426,971.

To all whom it may concern:

Be it known that I, JOHN AUERMILLER, a citizen of the United States, residing in Chicago, in the county of Cook and the 5 State of Illinois, have invented a new and useful Improvement in Window Awnings, of which the following is a specification.

My invention relates to window awnings that roll upon a roller in the middle of the 10 window.

The object of this invention is the provision of a window awning which shall be simple, durable, and efficient, and which may be manufactured and sold at comparatively 15 low cost.

Another object is to do away with the rope and pulley troubles experienced with other awnings of somewhat similar construction, and also to do away with the complicated parts of other awnings, such as 20 spring rollers, catch pulleys, slide rods, and cross bars, making it so simple that it can be put up and taken down easily and quickly, by even inexperienced hands.

25 In the drawings, Figure 1 is a front elevation of awning when it is rolled up or closed.

Fig. 2 is a side elevation of awning when it is unrolled.

30 Fig. 3 is a plan top view of cleat.

Fig. 4 is a side elevation of cleat bridged at the base, with an eye over the bridge.

Pulling rope 1, Figure 1, opens or unrolls the awning, at the same time winding up 35 rope 2, on the galvanized spool 6, on the end of roller 7, one half 15, of the awning goes up, the other half 16, goes down or out with the frame 9, which is pivotally secured to the lower face of the window 40 frame by brackets 17 and 18, as shown in Figure 2, rope 1, is fastened to the upper half of the awning in the middle at 8, runs to the top of window through pulley 3, then down through cleat 4.

45 Pulling rope 2, when the awning is unrolled or open, rolls awning up. Rope 2, is fastened to galvanized spool 6, runs through pulley 5, and through cleat 4.

The canvas or cloth is doubled and wound 50 around roller with folded edge tacked upon the roller, the two free ends of the canvas or cloth being on the outside of the roller

when wound, the lower piece is attached to and goes out with the frame, and the upper piece goes to the top of window with rope 1. 55

The cleat is bridged at the base so as to hold rope 2, as low as possible, for where screens are used in the windows, rope 2, would pass to the inside between the bottom of screen and the window sill, in the middle 60 of sill or in line with cleat, the screen being notched to let the rope pass freely allowing awning to be operated from the inside without moving screen.

I realize that considerable variation is 65 possible in the way the ropes are arranged.

I am aware that window awnings with spring rollers in the middle of the window, one half of the awning going up, the other half going down or out with the frame are 70 in use, but what I claim as new and an improvement is using a wooden roller and operating it entirely with ropes.

Having thus fully described my invention what I claim is new and desire to secure by 75 Letters Patent is:—

In a window awning the combination of a wooden roller 7, rotatably mounted at the middle of the window and with a spool 6, on the end, a frame 9, pivoted to the window 80 frame at a point below said roller, an awning material doubled, the doubled end fastened to and wound around said roller 7, one-half adapted to go to the top of window, the other half secured at its outer end to 85 said frame to go downward and outward therewith, a pulley 3, on the top of window casing, a cleat 4, secured to the window sill, said cleat being bridged at the base, with an eye over the bridge, a rope 1, fastened to 90 the top half of awning and passed through said pulley 3, then through said eye, a pulley 5, secured to the window sill at a point below said spool 6, a rope 2, fastened to said spool 6, and passed through the pulley 5, 95 then through cleat 4, all arranged as shown and described.

In testimony whereof I affix my signature in the presence of two witnesses.

JOHN AUERMILLER.
